CLAIM

The ornamental design for a lattice shelf, as shown and described.

DESCRIPTION

FIG. 1 is a front perspective view of a lattice shelf showing our new design;

FIG. 2 is a top plan view thereof, the bottom plan view being a mirror image thereof;

FIG. 3 is a front elevational view thereof, the back elevational view being a mirror image thereof; and,

FIG. 4 is a right side elevational view thereof, the left side elevational view being a mirror image thereof.
